UNITED STATES PATENT OFFICE.

CHARLES H. DE VOLL, OF SEATTLE, WASHINGTON, ASSIGNOR OF ONE-HALF
TO MARCEL BEAUDRY, OF ANACORTES, WASHINGTON.

DESIGN FOR A LAMP.

SPECIFICATION forming part of Design No. 33,391, dated October 16, 1900.

Application filed July 24, 1900. Serial No. 24,722. Term of patent 7 years.

To all whom it may concern:

Be it known that I, CHARLES H. DE VOLL, a citizen of the United States, (whose post-office address is at Seattle, Washington,) residing at Seattle, in the county of King and State of Washington, have invented and produced a new and original Design for a Lamp; and I do hereby declare the following to be a full, clear, and exact description of the same, reference being had to the accompanying drawing, forming a part thereof.

In the accompanying drawing the figure is a side elevation of a lamp embodying my design.

In the drawing, *a* denotes the reservoir or bowl of the lamp, which is substantially oval in cross-section and is provided with a downwardly-extending base *b*, a centrally-arranged supporting rim or projection *c*, and an ex-
tension *d*. From the reservoir *a* extends a

pipe *e* in a horizontal and then vertical manner, the said pipe near its upper end being turned in the form of a gooseneck *f*, its outer end being provided with a head *g*.

h represents a pipe which extends from the burner *j* in a horizontal and then a vertical manner to a point near the end *g* of the gooseneck *f*, at which point said pipe *h* is provided with a funnel end portion *i*.

Having now described my invention, what I claim as new, and desire to secure by Letters Patent, is—

The design for a lamp, substantially as herein shown and described.

In testimony whereof I hereunto affix my signature in presence of two witnesses.

CHARLES H. DE VOLL.
